[57] CLAIM

The ornamental design for the wine bottle display rack, as shown and described.

DESCRIPTION

FIG. 1 is a perspective view of one form of the wine bottle display rack of this invention;

FIG. 2 is a top plan view of FIG. 1;

FIG. 3 is a bottom plan view of FIG. 1;

FIG. 4 is a front elevation of FIG. 2;

FIG. 5 is a right side elevation of FIG. 2;

FIG. 6 is a rear side elevation of FIG. 2;

FIG. 7 is a left side elevation of FIG. 2;

FIG. 8 is a perspective view of a second embodiment of the wine bottle display rack of this invention;

FIG. 9 is a top plan view of FIG. 8;

FIG. 10 is a bottom plan view of FIG. 8;

FIG. 11 is a front elevation of FIG. 9;

FIG. 12 is a right side elevation of FIG. 9;

FIG. 13 is a rear side elevation of FIG. 9;

FIG. 14 is a left side elevation of FIG. 9;

FIG. 15 is a perspective view of a third embodiment of the wine bottle display rack of this invention;

FIG. 16 is a top plan view of FIG. 15;

FIG. 17 is a bottom plan view of FIG. 15;

FIG. 18 is a front elevation of FIG. 16;

FIG. 19 is a right side elevation of FIG. 16;

FIG. 20 is a rear elevation of FIG. 16; and,

FIG. 21 is a left side elevation of FIG. 16.
